UNITED STATES PATENT OFFICE.

THEODORE P. DRIVER, OF MELROSE, MASSACHUSETTS

ELECTRIC LAMP.

1,111,956.

Specification of Letters Patent. Patented Sept. 29, 1914.

Application filed May 15, 1914. Serial No. 838,708.

To all whom it may concern:

Be it known that I, THEODORE P. DRIVER, a citizen of the United States, residing at Melrose, in the county of Middlesex and 5 State of Massachusetts, have invented new and useful Improvements in Electric Lamps, of which the following is a specification.

My invention relates to portable electric lights, and its object is to provide a lamp 10 which is inexpensive and simple to construct, and which may be quickly and easily attached to the ordinary commercial type of dry cell battery in common use, thus dispensing with the necessity of carrying bulky 15 batteries when traveling, and yet enabling the traveler to have available at practically all times a powerful electric light of long duration, as batteries of the type to which my device is adapted are readily obtainable 20 everywhere.

My device consists of a main supporting member of conducting material, with an insulated portion which serves as a handle, bent into an inverted U, the extremities of 25 which are provided with flanges and apertures therein to engage the binding posts of a dry cell battery, thus securing the lamp to the battery and enabling the whole to be carried by the handle, and a metallic reflector secured to the main supporting member 30 and in electrical contact therewith containing a small incandescent lamp through which the flow of current from the battery is effected by a thumb screw on the main 35 supporting member adapted to make and break contact with the base of the lamp.

The well known type of pocket flash light in which an incandescent lamp and battery are contained in a single casing is wholly 40 inadequate to perform the functions of my device, as the small size battery necessarily employed has not the strength to furnish a continuous light of high power for any considerable period of time. I have been able 45 employing my device with an ordinary size dry cell battery to provide a light of sufficient candle power for forty hours without interruption, to enable a person to read fine print in a newspaper at a distance of one 50 hundred feet.

One of the principal advantages of my device resides in its specific construction, to be hereinafter described, as it is so simple that it can be manufactured at extremely low cost

and occupies much less space when detached 55 from a battery than the pocket flash lights referred to above.

My device will be found particularly useful in the camp and wherever a lantern is serviceable as it may be carried about easily 60 by the handle, set on the battery base on table or shelf, or suspended from wall or ceiling as convenience may require.

The accompanying drawing shows a side elevational view of my device attached to a 65 battery, parts being in section.

In the accompanying drawing, 1 is the combined handle, supporting member for the various parts, and current conductor. In the preferred form it comprises three sections, the two end sections 2 and 3 being composed of electric current conducting material, and the middle section 4 of insulating fiber or other preferred nonconductor to break the circuit through this portion of the 70 handle and prevent shock to the person carrying the lamp.

5 and 6 are rivets by which the section 4 is secured to the end sections 2 and 3.

7 and 8 are respectively flanges at the extremities of the end sections 2 and 3 provided with apertures 9 and 10 adapted to engage the battery terminal binding posts 11 and 12 of the battery 13.

14 is a metallic reflector secured to the 85 section 3 and in electric contact therewith.

15 is an incandescent lamp contained in the reflector 14 having one filament terminal electrically connected with the reflector. The other filament terminal is electrically 90 connected with the base 16.

17 is a thumb screw of conducting material in engagement with the screw threaded aperture 18 in the section 2 provided with an enlarged end portion 19 adapted to make 95 and break contact with the base 16. When the thumb screw 17 is turned up against the base 16 the circuit through the battery 13, section 3, reflector 14, lamp 15, thumb screw 17 and section 2 is closed and the lamp burns. 100 When the contact between the screw end 19 and the base 16 is broken the circuit and lamp are dead.

What I claim and desire to secure by Letters Patent is:

1. An electric lantern adapted to be attached to a battery comprising in combination a supporting member formed of three

connecting sections, each of the end sections being composed of current conducting material and the middle section of insulating material, and each of said end sections being adapted to engage at its free extremity a battery terminal, a reflector carried on said supporting member, an electric lamp contained in said reflector, one filament terminal of which lamp is connected with one 10 of said end sections and a contact device on the other of said end sections adapted to make and break contact with the other filament terminal of the lamp.

2. An electric lantern adapted to be attached to a dry cell battery comprising in combination a supporting member formed of three connecting sections, each of the end sections being composed of current conducting material and the middle section of 15 insulating material, and each of said end sections being adapted to engage at its free extremity a battery terminal, a reflector of conducting material containing an electric lamp supported on one of said end sections 20 and in electric contact therewith and with one filament terminal of the lamp, and a thumb screw in engagement with a screw threaded aperture in the other of said end sections and adapted to make and break contact 25

tact with the other filament terminal of the 30 lamp.

3. An electric lantern adapted to be attached to a dry battery comprising in combination a supporting member formed of three connecting sections, each of the end sections being composed of current conducting material and the middle section of insulating material, and each of said end sections being adapted to engage at its free extremity a battery terminal, a reflector of 35 conducting material carried on one of said end sections and electrically connected therewith, an incandescent lamp supported in said reflector and positioned to effect contact between said reflector and one filament 40 terminal of the lamp, and a contact device supported on the other of said end sections and electrically connected therewith adapted to make and break contact with the other filament terminal of the lamp. 50

In testimony whereof I have hereunto set my hand in presence of two subscribing witnesses, this thirteenth day of May 1914.

THEODORE P. DRIVER.
